CLAIM

The ornamental design for a feminine care package, as shown and described.

DESCRIPTION

FIG. 1 is a front perspective view of a feminine care package; FIG. 2 is a back view of the feminine care package of FIG. 1; FIG. 3 is a first side view of the feminine care package of FIG. 1;

FIG. 4 is a second side view of the feminine care package of FIG. 1;

FIG. 5 is a top view of the feminine care package of FIG. 1; and,

FIG. 6 is a bottom view of the feminine care package of FIG. 1.

In the drawings, the evenly spaced broken lines represent environmental structure and form no part of the claimed design; the dash-dot-dot-bash broken lines represent boundaries of the claimed design and form no part of the claimed design.

1 Claim, 4 Drawing Sheets
